UNITED STATES PATENT OFFICE.

ALEXANDER S. SPEER, OF CHICAGO, ILLINOIS, ASSIGNOR, BY MESNE ASSIGNMENTS,
TO UNITED STATES GYPSUM COMPANY.

PLASTER BOARD.

Application filed November 29, 1920. Serial No. 427,045.

My invention is an improvement in plaster board, and the invention has for its object to provide a board composed of plastic material, as for instance plaster, with facings of fibrous material, as for instance paper, and having means at its opposite side edges and if desired intermediate its side edges for reinforcing the plaster and holding it in place, and for providing nailing edges for the board.

In the drawings—

Figure 1 is a perspective view of a portion of board,

Figure 2 is a partial transverse section of the same,

And Fig. 3 is a sectional view of another embodiment of the invention.

Plaster board as usually constructed being composed of a body of plastic material and facing sheets of fibrous material has a tendency to chip and break at its edges during handling, as for instance in transportation, and there is also a liability to cracking and splitting of the edges during the placing of the board while nails are driven through the board. In order to provide a protection and reinforcement for the edges of the board, and in addition to provide nailing edges, I insert between the facing sheets at each side edge of the board inserts containing fibrous matter, as for instance strips of fibrous material having between them portions of the plaster forming the body of the board. These inserts may also be arranged longitudinally of the board at spaced intervals, and when so placed, and the board is cut along the line of the inserts into narrow lengths of board, each length will have an inset at each side edge.

In the embodiment of the invention shown in Figures 1 and 2, the improved board is composed of a body 1 of plastic material, as for instance plaster, and facings 2 of fibrous material, as for instance paper, the said facings being on the opposite faces of the body. Insets are arranged between the facings 2 at each side edge of the board, the said insets being secured to the facings in any suitable or desired manner, and these insets are

flush at their outer edges, or approximately so, with the edges of the facings.

Each inset in the present instance is composed of a tubular structure 3 of fibrous material, having a core 4 of plastic material, as for instance plaster Paris.

As shown in Figures 1 and 2, the tubular structures 3 of the insets are flattened between the facing sheets 2. It is obvious however that such structure need not be flattened, and that they need not be of circular or elliptical cross section. As shown in Figure 3, the board 5 has insets 6 which are formed by bending fibrous sheets into tubular form, square in cross section, and filled with plastic material. These insets are inserted in the same manner as shown in Figures 1 and 2, and in both constructions the facing sheets are secured to the insets.

What I claim is:

1. A plaster board comprising in combination, a plaster body having fibrous cover sheets adhering to the face sides thereof and reinforcing said board from edge to edge; and insets independent of the cover sheets lying at the side edges of said board between the margins of the cover sheets to reinforce the edges of the board, said insets comprising plaster covered with a tubular member of fibrous material along the board edges so as to provide a board which presents fiber covered side edges.

2. A fabricated board comprising a body of plaster and facing sheets of fibrous material, and having reinforcing insets between the facing sheets at the side edges of the board, said insets each comprising a tubular structure having a plaster core.

3. A fabricated board comprising a body of plaster and facing sheets of fibrous material and having reinforcing insets at the side edges of the board between the facing sheets to which said sheets are secured, said insets each comprising a flattened tubular member of fibrous material having a plaster core.

In testimony whereof I affix my signature.
ALEXANDER S. SPEER.
